UNITED STATES PATENT OFFICE.

GILBERT S. DEY, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

LENS-GRINDING MACHINE.

Application filed October 1, 1920. Serial No. 413,956.

To all whom it may concern:

Be it known that I, GILBERT S. DEY, a citizen of the United States, residing at Southbridge, in the county of Worcester and State of Massachusetts, have invented certain new and useful Improvements in Lens-Grinding Machines, of which the following is a specification.

This invention relates to improvements in grinding machinery and has particular reference to a novel and improved form of machine for use in the production of ophthalmic or similar high grade lenses.

Prior to my invention lenses have been produced through the use of a rotating member which may be either the tool or the lens block in combination with a loosely held opposed member. Difficulty was experienced in this type of construction, however, due to the fact that the spinning of the opposed member, particularly if the same were a lens, would produce concentric rings or wave effects on the surface so that in the past it has been necessary to apply a break up motion such as a transversely sliding action to said second member in order that satisfactory surfaces may be produced.

It is, therefore, the primary object of my present invention to produce a machine in which it will no longer be necessary to apply the additional power necessary for imparting movement to both of the parts, but in which the grinding movement may be applied to but one of the members, thus lessening the power required for the grinding operation, and in which the necessary break up movement to prevent the formation of the rings, wave effects or the like shall be automatically effected.

Other objects and advantages of my improved construction should be readily apparent by reference to the following specification taken in connection with the accompanying drawings, and it will be understood that I may make any modifications in the specific details of construction shown and described within the scope of the appended claims without departing from or exceeding the spirit of my invention.

Figure I represents a front elevation of a machine constructed in accordance with and embodying my improvements.

Figure II represents a plan view thereof.

Figure III represents an enlarged detail view of the tool. 55

Figure IV represents a diagrammatic view of the line of grinding movement of the upper member in my machine generated through the use of my improvement.

In the drawings, the numeral 1 designates the main base or frame of the machine, having journaled therein the lower spindle 2 suitably driven as by the belt 3. This spindle in ordinary use is provided on its upper end with the grinding tool 4 having a spherically curved surface to impart a con- trageneric curve to the lenses. These lenses may be one or more in number, as desired, and are preferably carried as by the block 6 which is retained in position as by the angularly adjustable upper spindle 7 slidably held as by the support 8 on the frame 9, and provided at its upper end with the weight 10 serving to urge the spindle and lens block in the direction of the grinding member. 75

It has previously been customary to have the frame 9 reciprocate carrying with it the pin or spindle 7, since in those instances where the pin or spindle has been stationary the driving of the grinding member 4 while causing a spinning action, producing grinding between the lenses and tool, would at the same time produce a plurality of concentric rings or wave surfaces.

My improvement in this form of grinding 85 consists in forming centrally of the upper face of the lens block 6 the upstanding flange or collar portion 12, formed interiorly with the teeth 13 providing an interior gear surface with which meshes the teeth 14 of the 90 drive pinion 15. This pinion is smaller by a number of teeth than the interior gear provided by the teeth 14 and has formed in its upper face the eccentrically disposed socket 16 adapted to receive the lower end 95 of the pin 7.

Whereas in the former machine in the absence of a cross motion the movement of the upper block was solely a spinning action about its center, in the case of my improved 100 construction as the grinding member 4 is driven and the friction between it and the lenses 5 tends to spin or rotate the lens block 6 through the support or retention in position of this member through the spindle 7, 105 pinion 15 and interior gear 13, in place of

a direct spinning movement there will be a spinning movement rolling around on the pinion 15 and at the same time an eccentric movement of the pinion and parts rolling 5 around thereon, with the result that the relative movement of the center of the lens block in place of spinning on a point, will be in the form of a continuous progressing trefoil form such as shown in Figure IV, or some 10 variation thereof, a four, five or other point figure being producible by suitable relating of the eccentricity and relative numbers of teeth of the pinion and internal gear.

It will, therefore, be seen that I have provided an improved simplified grinding machine, which having a single grinding part and stationary opposed part, will through 15 the form of connection between the stationary member and the grinding member, cause 20 the grinding member as it automatically spins though friction engagement with the grinding tool, to advance in a variable path, establishing a satisfactory break up movement, insuring perfect lens surfaces in place 25 of merely spinning producing wavy or defective surfaces, or instead of requiring additional power sufficient to constantly shift the upper portion of the machine and in this manner prevent defective surfaces.

30 While in the detailed description of the drawings I have particularly described the member 4 as the grinding tool and the member 6 as the lens bearing block, it is to be understood the lenses 5 may be mounted on 35 the member 4 and the member 6 may be the polisher without departing from my invention, but on the other hand with the production of extremely desirable results, the particular position of the parts being a matter 40 of personal determination, varying in the form illustrated according to the shape of surface to be ground, although it will be understood that it is not entirely dependent on this feature, since the block and

grinding tool might be made of contragene 45 ric curve or the like if desired.

I claim:

1. A device of the character described including a rotated grinding member, a rotatable lens holding member in frictional engagement therewith, one of said members having an internal gear on its back surface, a stationary spindle and a pinion of less diameter than the internal gear carried by the spindle and in mesh with the gear, substantially as and for the purpose described. 55

2. In combination with a rotated grinding member, a lens holding member having a socket, a connecting member having rolling engagement with the interior of the socket, 60 and a stationary positioning device eccentrically engaging the connecting member.

3. A machine of the character described including a rotated grinding member, an opposed rotatable lens holding member in frictional engagement therewith, said opposed member having an internal gear portion, a pinion of less size than the gear meshing therewith, and a stationary positioning device eccentrically engaging the pinion, substantially as and for the purpose described. 65 70

4. A machine of the character described including a rotatable grinding member, an opposed rotatable lens holding member in frictional engagement therewith, said opposed lens holding member having an internal gear portion, a pinion of less size than the gear meshing therewith, a positioning device eccentrically engaging the pinion, and means for angularly adjusting the positioning member, substantially as and for the purpose described. 75 80

In testimony whereof I have affixed my signature, in presence of two witnesses.

GILBERT S. DEY.
